UNITED STATES PATENT OFFICE.

THOMAS H. WYNN, OF CLEVELAND, OHIO.

AUTOMATIC FEEDING DEVICE FOR TACK MACHINES.

Application filed March 5, 1921. Serial No. 449,935.

To all whom it may concern:

Be it known that I, THOMAS H. WYNN, a citizen of the Dominion of Canada, residing at Cleveland, in the county of Cuyahoga 5 and State of Ohio, have invented certain new and useful Improvements in Automatic Feeding Devices for Tack Machines, of which the following is a specification.

This invention relates to automatic feeding devices for tack machines, and in some respects it is an improvement on the device shown in my U. S. Patent #1,102,625, the tack machine being of that type in which a strip of material is fed to the machine and 15 is reversed or turned over after each cut; and, the cut being on an angle, a V-shaped blank is severed at each operation.

In the ordinary tack machine an operator is required for about every six machines, 20 and his work consists in placing the strips of steel in the machine, as the strips are cut up. This replacing takes time and the time is multiplied by the number of machines, and the lost time therefore amounts 25 to considerable in the long run.

The object of the present device is to provide improved means for automatically feeding the strips of stock to the tack machine, the feeding being effected, in a general way, by automatically registering strips in succession with the barrel through which the strip is fed, the strips being brought 30 into position successively by a traveling carrier which can be loaded with a large number of strips and which is automatically actuated by the operation of the tack machine to feed the strips at properly timed intervals.

A further object of the invention is to provide means for governing the operation 40 of the carrier referred to.

A further object of the invention is to provide improved means for gripping and advancing the strip from the barrel, and presenting the same to the cutters of the 45 tack machine.

Other improvements in the details of the device will be apparent from the following description and the accompanying drawings.

In the drawing, Fig. 1 is a side elevation 50 of my machine shown as connected to a tack machine; Fig. 2 is a section on the line 2—2 of Fig. 1; Fig. 3 is a detail in section of one of the carrying fingers; Fig. 4 is a front elevation of a tack machine showing the 55 gripping mechanism mounted thereon; Fig.

5 is a perspective view of the gripping mechanism; Fig. 6 is a detail in section of one of the bearing brackets and the manner of mounting the shaft; Fig. 7 is a perspective view of the discharge end of the feed barrel; Fig. 8 is a vertical section of the parts shown in Fig. 7; Fig. 9 is a detail in side elevation of a latch which when released causes another strip of material to be fed into the barrel, and Fig. 10 is a top plan of Fig. 9.

Referring to the drawing, 1 indicates a frame or housing connected to a tack machine the base of which is indicated by 2, by a connecting member 3. Carried near the upper and lower ends of the housing 1, are shafts 4 and 5 on which are mounted sprockets 6 and 7. Chains 8 and 9 work on these sprockets and have bars 10, placed on an angle as shown, connected to them, the bars slanting downwardly toward the tack machine. Fingers 11 are rotatably mounted or hung near each end of the rods 10. These fingers are hooked or L-shaped, projecting downwardly at 12 from the rod 10, then horizontally as at 13 (Fig. 3) and then upwardly as at 14 (Fig. 1). A web 15 connects these three parts and forms with the part 13 a seat on which the metal strips, indicated in dotted lines at 16 in Fig. 3, are placed. The web 15 prevents them from sliding off the finger. The whole forms a traveling carrier which can be loaded in advance with a plurality of strips.

Attached to the housing 1 and spaced in front of the chains 8 and 9 are two parallel tracks 17 and 18 which form a guide for a vertical arm 19 which is attached to one end of a rack 20; ears 21 on the arm 19 riding above and below the rails 17 and 18.

The forward end of the rack 20 works between four rollers 22, two being on each side of the rack which rollers are mounted on the housing 1. The upper end of the arm 19 has a cup-shaped member 23 from which projects forwardly an arm 24 which is in the same plane with an arm 25 projecting outwardly from the housing 1, these arms being located in the path of the strips on the fingers 11. As the sprockets 6 and 7 revolve and the chains 8 and 9 are fed downwardly the rods 10, fingers 11 and metal strips 16 will also be fed downwardly until they reach the parts 24 and 25 which are placed as stated above in the path of the strips 16. These

parts 24 and 25 will then receive or pick up the strips 16 and the fingers 11 and connected parts will continue to travel down. Then as the rack 20 is released as will hereinafter be described, a weight 26 which is connected by a cable 27 to the arm 19 and rack 20 will cause the arm 19, cup 23 and arm 24 to move forwardly, carrying the strip 16 which has been deposited on the arms 24 and 25 into the feed barrel 28, which is constructed and is rotated or reversed substantially the same as that shown in my Patent #1,102,625, except at its forward end which will be described hereinafter.

15 A flat lever 29 is pivoted at 30 to a vertical post 31, and has pivoted to a depending bracket 32 a lever 33 which in turn has a pawl 34 pivoted at 35 to its upper end, a spring 36 tending to keep the forward end 20 of the pawl 34 up to engagement with the rack 20. Pivoted to the member 29 directly in front of the lever 33 is another pawl or 30 detent 37 which has a spring 38 tending to force the forward end up as shown.

25 A rod 39 which works the mechanism which rotates the barrel 28 back and forth (said mechanism being the same as shown in my said Patent #1,102,625) is connected to the lower end of the lever 33 and as it 30 moves back and forth it rocks the lever 33 on its pivot and consequently rocks the pawl 34. This moves the rack 20 forwardly and the detent 37 will hold the rack in this position while the pawl 34 is moving back to 35 engage another tooth. As the rack, and consequently the arm 19, nears its outermost position an adjusting screw 40 carried by the lower end of the arm 19 comes in contact with an arm 41 which is pivoted on a shaft 42, said arm 41 carrying a pawl 43 which engages a ratchet 44 which is keyed to the shaft 42. On the other end of the shaft 42 is a beveled gear 45 which meshes with a beveled gear 46 carried by the shaft 5. As 40 the shaft 42 and gears 45 and 46 are rotated the shaft 5 will be rotated and consequently the chains 8 and 9 and their correlated parts will be moved downwardly. When the rack 20 is released and drawn forwardly by 45 the weight 26 the arm 41 will be returned by a spring 47 to engage another tooth on the rack 44. An adjustable stop 48 limits the return movement of the arm 41.

The forward end of the lever 29 is bent 50 upwardly as at 49 and has a latch mechanism generally indicated at 50 which engages a catch 51 fastened to the tack machine. When the end of the strip in the barrel 28 passes a certain point in the barrel 55 it will release a mechanism hereinafter described which when the barrel is rotated will release the latch 50 and allow the forward end of the bar 29 to be drawn downwardly by a spring 52 thereby disengaging the 60 pawls 34 and 37 from the rack 20. This will

allow the rack 20 to be pulled forwardly by the weight 26 as heretofore described, forcing a new piece of material into the barrel. The upward movement of the rear end of the bar 29 will be limited by a stop 53 projecting outwardly from the member 3.

As the rack 20 nears the end of its forward movement it will come in contact with a sloping projection 54 on the upper edge of the bar 29 and will force the end 49 downwardly until the latch 50 engages the catch 51. This will bring the pawls 34 and 37 into engagement with the rack and it will be moved backward by the actuation of the pawl 34.

80 The latch member 50 consists of a sliding latch pin 55 held on the bar 49 by brackets 56 and 57, a spring 58 being wound around the reduced end 59 of the latch and interposed between the shoulder 60 and the 85 bracket 57. A bell crank 61 is pivoted at 62 to the bar 49 and the downwardly projecting arm 62 is slotted as at 63, in which slot a pin 64 on the latch 55 works. As will be readily seen, when the horizontal arm 65 of 90 the bell crank 61 is pressed downwardly the vertical arm 62 will be forced rearwardly thus forcing back the latch 55 against the pressure of the spring 58 and releasing it from the catch 51.

95 Within the forward end of the barrel 28 are sloping guide blocks 66 and 67 which are cut out as indicated at 68 and 69 to receive a finger 70 shaped as shown which is pivoted at 71 between two brackets 72. A spring 73, 100 coiled around the pivot 71 and having one end fastened to the barrel 28 at 74 and the other end fastened to the finger 70 at 75, will cause the finger 70 to swing to the position shown in the dotted lines in Fig. 8 when the end of 105 the strip 16 passes the end 76 of the finger 70. Then as the barrel is rotated the finger 70 will come in contact with the horizontal arm 65 of the bell crank 61 forcing it downwardly and thus releasing the latch 55 which 110 will allow the feeding mechanism to operate as hereinbefore described.

115 Projecting forwardly from the front end of the barrel 28 are two parallel spaced plates 77 which have their forward ends connected to a head piece 78 which is flat on its upper and lower sides as indicated at 79 and rounded at its ends as indicated at 80. A hole 81 in the head piece 78 is in alignment with an opening 82 in the end of 120 the barrel 28 through which the stock passes. The strip of stock is slightly wider than the plates 77, so that its projecting edges may be gripped as hereinbefore explained.

125 The nose piece 78 rests on the knife bed 85 of the tack machine and the material projects forward from the nose piece until it strikes the knife bed at which point the vertical knife of the ordinary tack machine cuts it. The nose piece 78 is shaped as shown 130

so that the tube will rise as it is turned, thus raising the material from the knife bed which is necessary in order to turn it. As is well known in the art, the vertical 5 knife cuts the material at an angle and the material is rotated so that it will cut first from one side and the next cut will be cut from the other side. This is so the material when cut off will be V-shaped.

10 Two jaws 83 and 84 are positioned between the end of the barrel 28 and the nose piece 78 and are so adopted as to engage the material at the edges of the plates 77 and hold it while a tack is being cut and then 15 move it forward for the next tack to be cut from it.

The jaws 83 and 84 are carried by two shafts 86 and 87, the shaft 86 being carried between bearing blocks 88 and 89 and 20 pivoted as shown in Fig. 6. This will allow for a slight adjustment of the shaft 86 in either direction. The block 83 is fastened rigidly to the shaft 86 by a set screw 90. The shaft 87 is in parallel alignment with 25 the shaft 86 and has one end offset as at 91 so that its center line will coincide with the center line of the shaft 86 extended. The block 84 is rigidly fastened to the shaft 87 by a set screw 92. An arm 93 pivoted at 30 94 is actuated by a cam 95 working against a roller 96 which is pivotally connected to the shaft 87 and moves said shaft back and forth as the arm 93 is moved by the cam 95, there- 35 by opening and closing the jaws. A vertical arm 97 is rigidly connected to one end of the shaft 86 and is adapted to be moved back and forth by a rod 98 which is actuated by a cam 99, the cams being carried by the main shaft 100 of the tack machine as de- 40 scribed in my said patent.

When the jaws 83 and 84 are brought together by the cam 95 and connected parts to grip the tack material, and while thus gripped the cam 99 actuates the lever 97 45 and turns the shaft 86 which in turn swings the jaws 83 and 84 forwardly, thus forcing the material forward into the tack machine in position for a blank to be cut, and when the blank is cut, instantly the jaws release 50 the grip, allowing the feed barrel to turn, and while the feed barrel is turning, the jaws swing back by means of a spring attached to the bed of the tack machine, in position for another grip.

55 The operation of the machine will probably be apparent from the above description, but may be briefly stated as follows:

When the strip being fed through the barrel 28 is almost used up it allows the finger 60 70 to swing up, and then when the barrel is turned said finger strikes the arm 65 and releases the latch 55 which pulls down the outer end of the lever 29 and releases the ratchet bar 20. The weight 26 then pulls 65 this ratchet bar toward the tack machine, to-

gether with the arm 19, and the arm 24 and cup 23 take up the strip of material and shove it endwise into the barrel 28, through which it follows the short end of the preceding strip, resetting the finger 70 and also 70 swinging the lever 29 back to the position shown in Fig. 1, reengaging the latch 55 and also the pawls 35 and 37. Then the operation of the tack machine actuates the lever 33 to slide the rack 20 back to original position, 75 at the end of which movement the screw 40 operates the pawl lever 41 to turn the shaft 42 and rotate the sprockets 7 causing the carrier to feed down another strip 16 onto the arms 24 and 25 for the next opera- 80 tion. The strips 16 will be loaded on the respective hooks 11, in advance, and when once loaded the machine will continue in automatic operation. New strips can be loaded in as occasion requires. 85

The invention is not limited to the particular mechanism shown and described, but various modifications may be made within the scope of the following claims.

I claim:

1. In a feeding mechanism the combination of a vertically arranged endless carrier, means to support strips of material in spaced relation thereon, means located in the path of said strips to pick up the same in succession from the carrier, and means to advance the strips so picked up, crosswise of the carrier. 90

2. In a feeding mechanism the combination of a pair of endless belts, rods extending 100 between the belts, hooks carried by the rods and adapted to support strips of material, arms projecting into the path of the strips as they are carried by the hooks, and adapted to pick up the strips from the hooks, and 105 means to advance one of said arms to feed the strips so picked up laterally with respect to the belts, whereby to feed said strips successively into a machine.

3. In a feeding mechanism the combination of a pair of endless belts, rods extending between the belts, hooks carried by the rods and adapted to support strips of material, arms projecting into the path of the strips as they are carried by the hooks, and 110 adapted to pick up the strips from the hooks, and means to advance one of said arms to feed the strips so picked up laterally with respect to the belts, whereby to feed said strips successively into a machine, 115 said means comprising a reciprocating bar connected to the movable arm and means automatically actuated by the machine to operate said bar. 120

4. In a feeding mechanism the combination of a pair of endless belts, rods extending 125 between the belts, hooks carried by the rods and adapted to support strips of material, arms projecting into the path of the strips as they are carried by the hooks, and 130

adapted to pick up the strips from the hooks, and means to advance one of said arms to feed the strips so picked up laterally with respect to the belts, whereby to feed said strips successively into a machine, the last mentioned means comprising a ratchet bar connected to the movable arm, a weight connected to said bar to move the same forwardly, and pawl mechanism engageable with the ratchet bar and automatically actuated by the machine to return the bar to original position.

5. In a feeding mechanism the combination of a pair of endless belts, rods extending between the belts, hooks carried by the rods and adapted to support strips of material, arms projecting into the path of the strips as they are carried by the hooks, and adapted to pick up the strips from the hooks, and means to advance one of said arms to feed the strips so picked up laterally with respect to the belts, whereby to feed said strips successively into a machine, the last mentioned means comprising a ratchet bar connected to the movable arm, a weight connected to said bar to move the same forwardly, and pawl mechanism engageable with the ratchet of the bar and automatically actuated by the machine to return the bar to original position, and means actuated by the return of the bar to advance the belts and deposit another strip of material on the arms.

6. In a feeding mechanism the combination of a rotary barrel through which strips of material are fed, an endless carrier provided with means to support a plurality of strips in spaced relation thereon, and means to successively advance said strips from said carrier into said barrel.

7. In a feeding mechanism the combination of a rotary barrel through which strips of material are fed, an endless carrier provided with means to support a plurality of strips in spaced relation thereon, and means to successively advance said strips from said carrier into said barrel, said means including a lever operatively engaging said means in one position, and an operating connection between the barrel and the lever controlling the position of the latter.

8. The combination with a cutting machine, of a feeding mechanism therefor including a rotary barrel through which strips of material are fed to the machine, a traveling carrier for said strips, means to actuate the carrier and advance strips therefrom into the barrel, and means carried by the barrel to control the time of said actuation.

9. The combination with a cutting ma-

chine adapted to operate on strips of material, of a rotary feeding barrel through which the strips are fed to said machine, an endless carrier adjacent the inlet end of the barrel and provided with means to carry spaced strips into alignment therewith, means automatically actuated by the machine to advance strips successively into the barrel, and means to govern the time of said actuation.

10. In a feeding mechanism the combination of an endless carrier provided with means to support a plurality of spaced strips of material thereon, a bar slidable across the carrier and provided with an arm located in the path of movement of the strips and adapted to pick up and shift strips successively from the carrier, means to reciprocate the bar, and means actuated by the reciprocation of the bar to automatically advance the carrier.

11. The combination with a tack machine or the like, of a rotary barrel through which material is fed to the machine, the end of said barrel being provided with a pair of spaced plates, and a head at the end of said plates, said head having a cam-shaped end adapted to lift the end of the barrel when it is rotated.

12. In a machine of the kind described the combination with a feeding tube 28, of the plates 77 at the end thereof and the head 78 at the end of said plates, said head having cam projections 80 at opposite sides thereof.

13. In a feeding mechanism the combination of a guide for a strip of material, a pair of jaws adjacent the end of said guide, a rock shaft on which said jaws are carried, one of said jaws being slidable on the shaft, a rod connected to the slidable jaw and working through the other jaw, and means to shift the rod lengthwise to open and close the jaws.

14. In a feeding mechanism the combination of a guide for a strip of material, a pair of jaws adjacent the end of said guide, a rock shaft on which said jaws are carried, one of said jaws being slidable on the shaft, a rod connected to the slidable jaw and working through the other jaw, and means to shift the rod lengthwise to open and close the jaws, said rod having a cranked end concentric with the axis of the rock shaft, whereby said rod may be turned.

In testimony whereof, I do affix my signature in presence of two witnesses.

THOMAS H. WYNN.
